CONTROLLING MECHANISM

David D. Jackson, Providence, R. I., and Erving
W. Tefft, South Attleboro, Mass.

Application December 4, 1933, Serial No. 700,818

10 Claims. (Cl. 236—76)

This invention relates to an apparatus for controlling a plurality of factors which have to do with bringing about the desired condition, and is described particularly in connection with the control of a boiler furnace altho the invention may be applied in other systems where there are a plurality of different control members or factors which enter into the obtaining of the desired final result.

10 An object of the invention is to provide a plurality of actuating devices which will be operated simultaneously to obtain any desired relative position between them at any given point of their movement.

15 Another object of the invention is the provision of actuating means for a plurality of different members having a like number of steps or positions with each step of one connected to a corresponding step in another so that the actuation will be simultaneous.

20 Another object of the invention is the provision of a pair of simultaneous step-actuating devices in which each of the steps is individually adjustable independent from all of the other steps 25 of the device and independent from the steps connected together in the two actuating devices.

Another object of the invention is the provision 30 of a control for a combustion system wherein the air and fuel are controlled at a series of steps with an arrangement by which the air which is to support the combustion of the fuel is supplied to the fuel in the correct volumetric proportion to produce the maximum percentage of carbon dioxide gas in the flue.

35 Another object of the invention is the provision of a control for obtaining the correct volumetric proportion of fuel and air which may be readily and universally adjustable for any number of a multiplicity of different points or relations of the 40 fuel valve and air supply control throughout their range of movements.

Another object of the invention is the provision 45 in such an apparatus of actuation on a step-by-step principle, wherein each of these steps may be separately adjustable for the actuation of either of the factors contributing to the desired result such for instance as both the air control and fuel so that the correct volumetric synchronization for the highest percentage of CO₂ gas in 50 the flue is obtainable for each step.

A further object of the invention is the provision 55 of an electric means which may be controlled at any remote point by some device responsive to steam conditions and which will thru circuits connected in parallel actuate a device for

the damper and another device for the fuel valve to cause these to move simultaneously in a relation which will volumetrically synchronize the fuel and air supplied thereto so that the highest percentage of CO₂ gas may be obtained in the 5 flue for each of the multiplicity of steps throughout the range of operations of both of these control factors.

A still further object of the invention is the provision of an electric control means which is 10 so arranged that should the current fail the fuel valve will shut off the supply of oil and the damper will permit the maximum flow of gases up the flue.

With these and other objects in view, the invention 15 consists of certain novel features of construction, as will be more fully described, and particularly pointed out in the appended claims.

In the accompanying drawing:—

Fig. 1 is a diagrammatic view illustrating the 20 general layout of our control and showing fragmentally the movable parts to which it is connected.

Fig. 2 is an enlarged detail of a single field in 25 one of our actuating units.

Fig. 3 is a diagrammatic view of a modified form of switch.

In the control of combustion, it is desirable to 30 so control the fuel which is fed and the air which is supplied thereto for combustion that the correct volumetric proportion of these two be obtained, and it is desirable that the air and fuel be 35 so volumetrically synchronized at all points throughout the range of movements of the oil valve and air control that the greatest percentage of CO₂ gas be obtained in the flue; and in order that this may be practically provided for, we have arranged a multiplicity of steps 40 throughout the range of movements of both the fuel valve and the damper with a means for simultaneously moving the fuel valve and damper

45 to corresponding steps in each of the actuating devices and we provide for an adjustment of these different steps throughout a range sufficient so that the desired volumetric synchronization of 50 these two products may be obtained for highest efficiency and we have also arranged for the operation of the actuating device synchronously thru electric means from a regulator responsive to steam conditions and also movable thru a series 55 of steps corresponding to the steps for the fuel and damper member above mentioned; and the following is a more detailed description of the present embodiment of this invention illustrating

the preferred means by which these advantageous results may be accomplished:—

With reference to the drawing, we have shown a fuel valve at 10 which controls the amount of fuel fed thru the conduit 11 to the combustion chamber 13 of a boiler furnace. At 15, we have illustrated a flue pipe which is controlled by a damper 16 for controlling the amount of flue gases up the chimney, which thus controls the 10 vacuum in the fire box and the volume of the intake air into the combustion chamber.

At 20, there is illustrated one type of regulator which will move in response to steam conditions in the boiler in a series of different steps, that 15 shown here being illustrated as ten steps along the notches 21, which causes the actuation of a rod 22 by reason of hydraulic power thru the cylinder 23. The type of regulator shown being that disclosed in the Kimball Patent No. 1,597,202, 20 August 24, 1926, altho it will be understood that we may use other regulators which will serve to produce a movement such as produced in the rod 22, which regulators may be of a smaller and less powerful type than at present used by us, the 25 regulators serving only to produce in this invention a movement which will correspond to or be affected by, the steam conditions in the boiler or by some other result which it is desired to obtain by the control of a plurality of factors entering 30 into the obtaining of such desired result.

In order to control the damper, we have provided a unit designated generally 25, consisting of a plurality of electrical coils or fields 26, 27, 28, 29, 30, 31, 32, 33, 34 and 35 which are arranged coaxially and suitably adjustably supported in a cylinder 36 by means of fingers 37 extending thru a slot 38 in the cylinder and clamped in adjusted position by bolts or other suitable holding means, the details of which are not specifically 40 shown.

These fields may be adjusted along the cylindrical part 36 to any desired position therein, and thru the center of each of these annular fields there extends a core 39 of non-magnetic material 45 throughout its length except for a short section 40 of magnetic material which is of a length sufficient so that when a field is electrically energized it will draw the magnetic section 40 to a position within the particular magnetic field energized and thus will cause movement of the core 39 inserted thru the coils, as the different coils are energized one after the other, progressively, from one end of the unit to the other.

In the arrangement which we have illustrated, 55 the unit 25 is vertical and the core 39 is connected to a lever 41 which is slotted as at 42 with a pin 43 extending thru it and thru the core 39 and by reason of this vertical arrangement we may provide a weight 44 secured to the end of the core 60 39 in cases where the core is not sufficiently heavy to cause it to drop quickly by gravity so that should the energy fail in all of the fields the weight would cause the damper to be moved to open position to permit free passage of gases up 65 the flue.

In order to control the fuel valve 10, we have provided another unit 45 which is similar to the unit 25 just above described, which controls the damper. This unit 45 consists of a series of fields 70 46, 47, 48, 49, 50, 51, 52, 53, 54, and 55, each of which is adjustably supported in a cylinder casting 56 having slots 57 therein thru which pins 58 extend to suitably support the field when clamped in adjusted position in the unit. A core 75 59 extends thru the annular fields, which is of

non-magnetic material and is provided with a section 60 of magnetic material so that as any of the fields are energized this section of the core will be moved into a position within the center of the field so energized. This core at the upper end is 5 connected to a lever or member 61 having a slot 62 therein with a pin 63 extending thru it and thru the rod 59. This lever is pivoted as at 64 and its opposite end is connected to the lever 67 by an adjustable link 65 having a turn buckle adjustment 66 therein which serves to provide a different movement to the valve 10 for opening and closing the same for the control of the fuel to the combustion chamber.

The fuel valve 10 is closed when the lever arm 15 67 is in raised position and the damper is opened when the member 41 is in its lowest position. On the end of the core 69, there is a weight 68 which is added to the core in cases where the core is not sufficiently heavy to drop to close the valve 20 should energy fail to be supplied to any of the fields.

By the arrangement of the fields in this manner we provide in each of the units 25 and 45 a series of steps so that the damper or fuel valve 25 will move to these different predetermined positions and there be maintained. The steps in each of these units will be the same in number, which we have here illustrated as ten and the regulator will also be such that it will have this corresponding 30 number of steps as at 21, which is also here illustrated as ten in number.

We provide a contact plate 70 having contacts thereon 71, 72, 73, 74, 75, 76, 77, 78, 79 and 80 over which a contact arm 81 may wipe actuated by 35 the member or arm 82 having a slot 83 therein with a pin 84 movable in the slot and connected to the actuating rod 22. The contacts 71 to 80 will be so closely arranged with reference to the contact arm that the contact arm will engage the 40 contact 72 before it leaves the contact 71 and will engage the contact 73 before it leaves the contact 72 and so on, whereby there will never be any interruption in energy supplied to some one of the fields of each of the units.

The fields 26 and 55 are connected in parallel thru a suitable circuit comprising line 90 which is connected to the contact 71 by a lead 91 there being a common ground return 92 leading to the source of energy, not shown, and from this source 50 of energy back to the contact arm 81 thru the line 93, this latter serving as a part of each of the circuits to be hereinafter designated. The field 27 is connected to the field 54 thru the line 94 also connected to a contact 73 thru the lead 95 55 and so on, each of the fields in one unit is connected to a corresponding field in the opposite unit in the inverse order, in order to obtain the corresponding relation desired between the fuel and air supplies.

In setting our control we will provide energy to one of the fields, say for instance the fuel valve unit, to hold this valve in a certain desired position and maintain a predetermined flow of fuel to the combustion chamber. For instance, if 65 the field 46 were set to supply the maximum amount of fuel to the combustion chamber, we will then adjust the field 35 to the proper position in the cylinder 36 so that with a CO₂ indicator the maximum amount of CO₂ will be obtained in the flue whereupon this field will be clamped in position and the setting of fields 35 and 46 will be fixed. We will then energize the field 47 to pull down the core 59 and supply a lesser amount of oil and then set the field 34 75

so that with this lesser amount of oil the maximum CO₂ percentage will be obtained in the flue after which the coil 34 will be clamped in position, all of which takes place without affecting the adjustments of the previous fields set. We will then carry forwardly this operation of setting each of the fields so that the maximum CO₂ percentage is obtained in the flue for each step or position whereupon we will have a relation for each of the steps throughout the range of operations of each of the control factors of air and fuel as to obtain the greatest efficiency.

With an arrangement of this character, it is not necessary that we have a straight line fuel valve acting to produce equal increments of fuel at each step action of the range of operations as the variations in the positions of each of the fields 46 to 55 inclusive will permit us to obtain equal flow by different steps of manipulation of the valve so that any type of valve may be used. We prefer, however, to use a straight line flow and more evenly distribute the fields in the unit 45; also by this arrangement the fields and their adjustments we may compensate for any varying factors due to the swinging of the arms of the valves about a curved line rather than a straight path of movement. This also holds true for the damper. We may also provide adjustable contacts 11 to 80 inclusive so that any variations due to the swinging of the arm 81 may be compensated for by the adjustment of these contacts so as to have the contact member 70 conform to the straight line movement of the rod 22. We may have as an alternative a series of straight line contacts illustrated in Fig. 3, at 100, and provide a wiper 101 on the rod 22 to move over these contacts, whereby the direct straight line relation in movement is obtained. By this arrangement of adjustments we may compensate for irregularities in the swinging parts where it is desired that the swinging parts be used rather than straight line motion. We may also arrange for equal flows of fuel or air, or various flows of fuel and air to be compensated for that the desired volumetric synchronization of the fuel and air may be obtained.

As above pointed out, the units 25 and 45 may be employed for controlling two other cooperating factors to produce the desired result, the same being actuated by means of some device responsive to the conditions of the desired result, such as the steam conditions here used for illustration.

The foregoing description is directed solely towards the construction illustrated, but I desire it to be understood that I reserve the privilege of resorting to all the mechanical changes to which the device is susceptible, the invention being defined and limited only by the terms of the appended claims.

We claim:

1. Control means for two differently movable cooperating factors to bring about a desired result, comprising means movable in response to conditions desired, movable means operating one factor effecting the conditions desired, movable means operating another factor effecting the conditions desired, separate electrical controls operable in different steps for each of said factor means, and means operated in a corresponding number of steps and operated by the first said movable means for simultaneously operating said electrical step controls, each of said steps being individually adjustable independently of the other steps for obtaining the desired factor ratio.

2. Control means for two different cooperating factors, comprising a first movable member and a second movable member, means for moving each of said members, each means comprising a plurality of coaxial electrical fields and a common core extending thru said fields and having a section adapted to be moved to within the excited field, each field in one moving means being connected in parallel with a field in the other moving means whereby said members are moved simultaneously to desired relative positions, each field in each means being individually adjustable to vary the relative positions of said movable members.

3. Control means for two different cooperating factors, comprising a first movable member and a second movable member, separate means for moving each of said members, each means comprising a plurality of coaxial electrical fields and a common core extending thru said fields and having a section adapted to be moved to within the excited field, each field in one moving means being connected in parallel with a field in the other moving means and in inverted relation whereby said members are moved simultaneously through different amounts of movement to desired relative positions, each core being provided with means to effect a movement of the core to one extreme position of its range of movements upon failure of electrical energy in the electrical fields.

4. Combustion control means for a boiler furnace, comprising a regulator capable of moving step by step in response to steam conditions, a fuel feed valve and a damper, electrically operated means capable of moving in corresponding steps for moving said valve and damper, said means being connected to the regulator, each of said steps being independently adjustable.

5. Combustion control means for a boiler furnace, comprising a regulator capable of moving in response to steam conditions, a fuel feed valve and a damper, electrically operated means for moving said valve and damper including means for simultaneously effecting any desired relative positions of said valve and damper according to a predetermined setting, said last named means being connected to said regulator, and means to open said damper and close said valve upon failure of energy in said electrical means.

6. Combustion control means for a boiler furnace, comprising a step action regulator capable of moving in response to steam conditions, a contact arm movable by said regulator, a plurality of contacts in position to be engaged by said arm at each step action of the regulator, a damper and a fuel feed valve, means for moving said damper, and means for moving said valve, each means comprising a plurality of coaxial electrical fields, a common core for said fields having a section adapted to be moved within the field energized and a plurality of circuits, each circuit connecting in parallel one of said contacts and one of the fields of said damper and valve moving means.

7. Combustion control means for a boiler furnace, comprising a step action regulator capable of moving in response to steam conditions, a contact arm movable by said regulator, a plurality of contacts in position to be engaged by said arm at each step action of the regulator, a damper and a fuel feed valve, means for moving said damper, means for moving said valve, each means comprising a plurality of coaxial electrical fields, a common core for said fields hav-

ing a section adapted to be moved within the field energized and a plurality of circuits, each circuit connecting in parallel one of said contacts and one of the fields of said damper and valve moving means, and means for adjusting each of said coaxial fields independently of the other fields.

8. Combustion control means for a boiler furnace, comprising a step action regulator capable of moving in response to steam conditions, a contact arm movable by said regulator, a plurality of contacts in position to be engaged by said arm at each step action of the regulator, a damper and a fuel feed valve, means for moving said damper, and means for moving said valve, each means comprising a plurality of coaxial electrical fields, a common core for said fields having a section adapted to be moved within the field energized and a plurality of circuits, each circuit connecting in parallel one of said contacts and one of the fields of said damper and valve moving means, and means for adjusting each of said coaxial fields independently of the other fields, and each of said contacts also being individually adjustable.

10. Combustion control means for a boiler furnace, comprising a step action regulator capable of moving in response to steam conditions, a contact arm movable by said regulator, a plurality of contacts in position to be engaged by said arm at each step action of the regulator, a damper and a fuel feed valve, means for moving said damper, and means for moving said valve, each means comprising a plurality of coaxial electrical fields, a common core for said fields having a section adapted to be moved within the field energized and a plurality of circuits, each circuit connecting in parallel one of said contacts and one of the fields of said damper and valve moving means, and means for adjusting each of said coaxial fields independently of the other fields, and each of said contacts also being individually adjustable.

9. Combustion control means for a boiler furnace, comprising a step action regulator capable of moving in response to steam conditions, a contact arm movable by said regulator, a plurality of contacts in position to be engaged by said arm at each step action of the regulator, a damper and a fuel feed valve, means for

moving said damper, means for moving said valve, each means comprising a plurality of coaxial electrical fields, a common core for said fields having a section adapted to be moved within the field energized and a plurality of circuits, each circuit connecting in parallel one of said contacts and one of the fields of said damper and valve moving means, and means for adjusting each of said coaxial fields independently of the other fields, and each of said contacts also being individually adjustable.

10. Combustion control means for a boiler furnace, comprising a step action regulator capable of moving in response to steam conditions, a contact arm movable by said regulator, a plurality of contacts in position to be engaged by said arm at each step action of the regulator, a damper and a fuel feed valve, means for moving said damper, and means for moving said valve, each means comprising a plurality of coaxial electrical fields, a common core for said fields having a section adapted to be moved within the field energized and a plurality of circuits, each circuit connecting in parallel one of said contacts and one of the fields of said damper and valve moving means, each of said cores being provided with means to effect a movement of the valve to closed position and the damper to open position upon failure of energy in the electrical fields.
